EDGE ROLL FOR UPHOLSTERY

Barney Boersma, Grand Rapids, Mich., assignor to Sackner Products, Inc., Grand Rapids, Mich.

Application March 5, 1953, Serial No. 340,563

10 Claims. (Cl. 155—184)

This invention relates to improvements in edge rolls for upholstering.

The main objects of this invention are:

First, to provide an edge roll for upholstering which while effective in maintaining its cross sectional shape when installed is bendable to conform to the part to which it is applied, as for example, one having reverse or compound curves.

Second, to provide an edge roll for upholstering spring assemblies and other upholstered objects such, for example, as furniture and the like which may be economically produced and readily applied to a structure.

Third, to provide a core element for bendable edge rolls which may be readily produced in the desired cross sectional shapes.

Fourth, to provide an edge roll which while maintaining its shape and performing its function when applied has sufficient bendability or flexibility so it can be wound onto rolls or on spools.

Fifth, to provide edge rolls having these advantages which may be economically produced and has substantial resilience and at the same time maintains its shape even when flexed or bent.

Objects relating to details and economies of the invention will appear from the description to follow. The invention is defined and pointed out in the claims.

A preferred embodiment of the invention is illustrated in the accompanying drawing, in which:

Fig. 1 is a fragmentary plan view of an edge roll embodying my invention, shown in reversely bent form to illustrate its flexibility and adaptability.

Fig. 2 is an enlarged fragmentary perspective view with the core member partially extended to illustrate structural details thereof.

Fig. 3 is a fragmentary plan view of the stock from which the core member of Figs. 1 and 2 is formed.

Fig. 4 is an enlarged fragmentary horizontal section of a portion of the bellows folded core member.

Fig. 5 is a fragmentary perspective view of a modified form or embodiment of my invention.

Fig. 6 is a fragmentary plan view of the core member of Fig. 5 in extended form to illustrate the details thereof particularly in the matter of shape.

The edge roll of my invention illustrated in the accompanying drawing is desirably made in considerable lengths and cut into sections of appropriate length for use.

The edge roll of my invention comprises a core member designated generally by the numeral 1. A resilient padding 2 is wrapped around the core member and a flexible covering 3 desirably of loosely woven fabric such, for example, as burlap is wrapped around the padding. The preferred means for associating and securing these parts in assembled relation will be apparent as the description proceeds.

The core member 1 is desirably formed of a strip of embossed paper stock designated generally as 4. This strip is conformed to provide a connected series of segments 5 of the same general peripheral shape, the

2

adjacent sections being foldably connected at 6. In the embodiment shown in Figs. 1 to 3 these segments have upwardly curved upper edges 7 and straight bottom edges 8, the connection for the segments being of substantially less length than the vertical width of the segments.

The conformed strip, as shown in Fig. 3 is bellows folded upon itself with the segments disposed vertically and transversely of the core member.

The resilient padding 2 is desirably of felted fibrous material such, for example, as felted jute and is wrapped around the core member with its edges 9 projecting from the inner side of the core member in overlapping relation and constituting an attaching flap element.

The covering 3 is wrapped around the padding material with its edges in lapping relation to the attaching flap element. A longitudinal row of stitches 10 is disposed through the attaching flap comprising the attaching flap element of the padding member and the lapping covering closely adjacent to the body of the roll. There is also an outer row of stitching 11 adjacent the outer edges of the attaching flap parts, the stitching being desirably of the overcast type.

To prevent substantial unfolding or extension of the core member when the edge roll is cut into sections I preferably provide a longitudinal row of stitches 12 extending through the body portion of the roll, that is, through the covering, the padding and the core member.

The edge roll thus formed is flexible or bendable and may be bent without materially affecting its resiliency. It may be bent generally horizontally as indicated in Fig. 1 and also vertically so that it may be conformed to fit various articles to be upholstered. This bendability is also of material advantage in that it permits the merchandising of the edge roll in substantial lengths in the form of rolls or wound on spools so that it may be cut in the desired lengths or sections for use. I preferably employ embossed paper stock, as shown in Fig. 4, although other forms of stock may be used if desired.

In the embodiment shown in Figs. 5 and 6 the segments 13 of the core member 14 corresponding to the core member 1 are of a general pear shape and disposed with the small ends thereof inwardly. The segments are joined for bellows folding as in the embodiment of Figs. 1 to 4. In this embodiment the reinforcing strip 15 is disposed at the inner edge of the attaching flap and embraced and retained by the covering 3.

A beading or attaching strand 16 is disposed in a fold 17 of the covering and secured by the stitches 18. This beading strand and reinforcing strip are arranged substantially as shown in the Cook and Hormuth Patent No. 2,615,504 issued October 28, 1952, thus particularly adapting the edge roll for attachment to a spring structure as is illustrated in the aforesaid patent.

I wish to point out that by thus forming the core member edge rolls various cross sectional shapes may be readily produced. Edge rolls embodying my invention may be very rapidly and economically produced and while substantially yieldable and bendable maintain their shape under relatively severe stresses or loads.

The forming of the core as I have illustrated provides very substantial flexibility or bendability while at the same time maintaining cross sectional shape.

I have illustrated and described my invention in a highly practical embodiment thereof. I have not attempted to illustrate or describe other embodiments or adaptations as it is believed that this disclosure will enable those skilled in the art to embody or adapt my invention as may be desired.

Having thus described my invention, what I claim as new and desire to secure by Letters Patent is:

1. A bendable edge roll for use in upholstery comprising an elongated body member including a resilient

core member formed of an elongated strip of fibrous stock bellows folded upon itself providing a series of connected segments disposed transversely of the core member in vertically edgewise side by side relation, the segments having edges conformed generally to the cross section of the core member, a resilient padding around the core member, and a flexible covering wrapped and secured around the padding.

2. A bendable edge roll for use in upholstery comprising an elongated body member including a resilient core member formed of an elongated strip of fibrous material bellows folded upon itself providing a series of segments disposed transversely of the core in vertically edgewise side by side relation, a resilient padding of sheet material wrapped around the core member with its edges extended at the inner side thereof and disposed in overlapping relation constituting an attaching flap element, and a fabric covering wrapped around the padding with its edges in lapping relation to said attaching flap element and secured thereto, there being a longitudinal row of stitches through the covering and the padding element closely adjacent the core member.

3. A bendable edge roll for use in upholstery comprising an elongated body member including a resilient core member formed of an elongated strip of fibrous material bellows folded upon itself providing a series of segments disposed transversely of the core in vertically edgewise side by side relation, the segments being of general pear shape and disposed with their narrower edges inwardly, and a flexible covering secured around the core.

4. An edge roll comprising a resilient core member formed of an elongated strip of embossed fibrous material bellows folded upon itself providing a series of segments disposed vertically edgewise and transversely of the core member and in side by side supporting relation, the segments having approximately straight bottom edges and upwardly curved top edges, the connections for the segments being of substantially less length than the vertical width of the segments, for the core member.

5. An edge roll comprising a resilient core member formed of an elongated strip of embossed fibrous material bellows folded upon itself providing a series of segments disposed vertically edgewise and transversely of the core member and in side by side supporting relation, a padding material wrapped around the core member with its edges disposed in overlapping relation at the inner side of the core member and constituting an attaching flap element, and a flexible covering wrapped around the padding with its edges in lapping relation to the said attaching flap element, the edges of the covering being secured to each other through the said attaching flap element.

6. An edge roll comprising an elongated core member formed of a strip of paper stock of substantial thickness

and conformed to provide a series of foldably connected segments of a peripheral shape corresponding to the cross section of the core member, adjacent sections being foldably connected at one vertical edge, the strip being bellows folded with adjacent segments disposed in vertically edgewise side by side supporting relation, and a flexible covering.

7. A bendable edge roll comprising a resilient core member formed of an elongated strip of embossed fibrous sheet material bellows folded upon itself providing a series of connected segments disposed transversely of the core member and in vertically edgewise side by side relation, and a flexible covering for said core member closely embracing the same and acting to hold adjacent segments of the core member in supporting relation to each other and in their vertically edgewise disposed position.

8. An edge roll comprising a resilient core member formed of a strip of yieldable material of self-supporting stiffness bellows folded upon itself providing a connected series of segments, the segments being shaped to the cross section of the core member and being disposed transversely of the core member in vertically edgewise side by side relation, and a flexible covering for said core member embracing the same and acting to hold adjacent segments of the core member in supporting relation to each other.

9. A core member for edge rolls comprising a strip of yieldable material of self supporting stiffness bellows folded upon itself providing a connected series of segments, the segments being shaped to the cross section of the core member and being disposed vertically edgewise side by side and transversely of the core member.

10. An edge roll comprising an elongated core member formed of a strip of stock of yielding but substantially self-sustaining material bellows folded upon itself to provide a series of connected segments, the segments being disposed in side by side supporting relation vertically edgewise and transversely of the edge roll, a flexible covering secured around the core member to embracingly support the segments thereof, and a longitudinal row of fastening elements disposed through the covering and the core member for limiting the longitudinal movement of the segments of the core member within the covering.
